NILS D. LEVIN, OF COLUMBUS, OHIO, ASSIGNOR TO THE JEFFREY MANUFACTURING COMPANY, OF COLUMBUS, OHIO, A CORPORATION OF OHIO.

AXLE JOURNAL BOX.

1,414,782.

Specification of Letters Patent.

Patented May 2, 1922.

Application filed July 28, 1914. Serial No. 853,770.

To all whom it may concern:

Be it known that I, NILS D. LEVIN, a citizen of the United States, residing at Columbus, in the county of Franklin and State 5 of Ohio, have invented certain new and useful Improvements in Axle Journal Boxes, of which the following is a specification, reference being had therein to the accompanying drawing.

10 This invention relates to axle journal boxes such as are used with locomotives and cars having rotary axles rigid with their wheels. One of the objects of the invention is to provide a new and useful arrangement 15 of the axle boxes and their immediate adjuncts in relation to the truck body and the wheels, respectively. Another object is to make a novel provision for controlling or limiting the movements of the axle and the 20 body frame in relation to each other; another is to provide a novel mounting of the axle in its box to permit access to the structural elements which effect the limiting or control above referred to, and to adjust or remove 25 the thrust elements, and permit the substitution of others.

In the drawings:

Fig. 1 is a side elevation of a part of a locomotive provided with my improvements; 30 Fig. 2 is a view taken in section through a part of the truck body, and showing a wheel, its axle box and part of the axle, in plan view;

Fig. 3 is a central vertical section of the 35 box showing the axle box when its relatively movable parts are in working positions;

Fig. 4 is a similar vertical section, but showing the closure element of the box in its open position.

40 I will first describe the specific form of mechanism which is illustrated in the drawings, and more or less in detail.

1 represents the outer vertical side wall or plate of the body part or frame part of a 45 mine locomotive. These are now generally made by casting or as sections of sheet metal. As shown, this part of the truck body has its outer surface situated substantially continuously in one vertical plane, and the parts 50 to be described are so designed as to lie between the outermost planes at the two sides of the car. Cars or locomotives of this special sub-class are intended for use in mine entries or passageways where the side walls 55 of rock or coal frequently come close to the

track lines; and by arranging the parts in the way which I have shown there are no projections to impinge upon or be struck by walls or objects close to the track.

This wall 1 is formed with an aperture 60 of suitable size, or with a wide slot which extends upward from its lower edge.

2, 2 are frame and spacing bars arranged vertically at the edges of each aperture and on the inside of the truck plate 1. To the 65 inner faces of these are secured the vertical plates 3, with their inner edges projecting somewhat beyond the bars 2 to provide guides for the axle box.

At the bottom of the aperture a cross bar 70 6 is arranged which stiffens the frame, holds the two side edges in the proper plane, and prevents displacement of the journal box, the latter being particularly liable to occur in case the locomotive is derailed.

75 The journal box is indicated at 5. It is formed with an upper part 5^a, a lower part 5^b and connecting side parts; and in the latter there are formed grooves 4 which fit the guide edges of the plates 3, the box being 80 allowed a vertical play relative to the truck body. 7, 7 are upwardly opening sockets formed in the upper part of the box, and in these are seated the springs 8. 9 is a bar, preferably of angle metal, which is rigidly 85 riveted to the truck plate 1, the horizontal part of the angle being near the planes of the upper edge of the aperture in the side wall and bearing downward upon the tops of the springs. 10 indicates the bearing 90 piece or bushing, customarily made of brass, and arranged to rest and bear upon the journal part 11 of the axle 11^a. The weight of the truck part of the locomotive or car bears 95 downward through the parts at 9, 8, 5 and 11 upon the wheel 12, and this in turn on the rails 13.

100 The box 5 is formed with an interior chamber, extending axially of the axle and its journal 11, this chamber not only receiving the journal, but being so shaped as to provide an oil passage from the supply orifice at 5^c downward around the bushing to a somewhat enlarged bottom cavity 14. The outer end part of the box is so formed 105 as to provide vertical guides and to these are fitted a movable closure or cover 15, the guides on the box being indicated at 15^a, and the side edges of the closure being rebated so as to provide opposing guide parts at 110

15^b. The top wall 5^a of the box has a lip at 5^d which lies outside of and forms a tight joint with the upper rebated part of the closure. When the latter is in place it tightly 5 closes the outer end of the interior chamber of the box, and prevents the escape of lubricant or the entrance of dust or foreign material.

Preferably the inner face of the cover or 10 closure is substantially continuous from bottom to top and without projections. It is held either in its open position or in its closed position by means of a lock device at 17 which, as shown, consists of a sliding 15 pin or rod mounted in apertures in lugs on the bottom wall 5^b of the box, the spring tending to force the lock pin outward. When the cover 15 is in closed position the lock piece is held firmly below it. When 20 it is desired to open the cover or closure it is merely necessary to push the lock pin back a short distance, and thereupon the cover can drop or be pushed downward. The lock, however, prevents the cover from dropping 25 entirely from the box for it is provided with a seat at 18 for the point of the lock pin to automatically move into. As the inner face of the cover or closure is smooth and continuous, as above described, the point of the 30 lock pin will slip over this surface until the notched part at 18 reaches it when it automatically seats itself.

A socket is formed in the end of the journal 11, and into this there is tightly fitted 35 a thrust element 20. An opposing thrust element 19 is seated in the cover or closure 15. Preferably the part at 20 is a hardened 40 steel pin driven into the shaft at its axis, and the companion or opposing part at 19 is a hardened steel plate which is tightly fitted 45 into a seat. It can be fastened in any suitable way; upsetting the metal of the cover at points adjacent to the edges of the thrust piece being sufficient.

These thrust taking parts at 19 and 20 50 are so shaped, arranged and related that the endwise thrust of the axle is taken at points directly at or adjacent to its axis.

Heretofore the parts of similar structures 55 have been so made and related that the longitudinal thrust of the axle has been transmitted directly from the wheel hubs to the boxes either directly or by means of wearing plates. The surfaces which take the 60 thrust and contact are so located as to be exposed to the wearing action of grit and foreign material, and, moreover, in such way that lubricating them is difficult. The wear is excessive, and frequent separations 65 of the parts are necessary in order to substitute new wearing devices.

With parts made in the way I have shown and described the wear resulting from end thrust is reduced to a minimum and the 70 contact points are brought to a position

where they are not only protected from the entrance of dust and foreign material, but are readily lubricated, the axle taking up the lubricant and distributing it not only over its cylindrical surface, but delivering 75 more or less of it at its ends where it reaches these contact points.

If, however, after long intervals of use, it is found that wear has occurred at the axially arranged thrust surfaces, it is merely 75 necessary to drop the cover or closure 15 downward and then by the blow of a suitable tool through the aperture 21 dislodge the plate 19 and insert another, and remove the thrust pin at 20 and insert another. One 80 way for readily accomplishing the latter is to form a few turns of an external thread at the outer end of the pin, prior to inserting it, and then, when the pin is to be withdrawn, rotating a suitable nut upon this 85 threaded end which will quickly draw it loose.

Having thus described in detail the construction and arrangement of parts presented in the drawings for the purpose of 90 illustrating my invention, it will be seen that the essential feature of the latter can be maintained without necessarily employing or following all of these details. The closure or cover part 15 may be regarded as 95 a holder for a thrust taking element, and although I prefer at present to have it carried by such a holder, it will be seen that there can be modifications in this respect. And, again, the thrust taking element which 100 is secured to the shaft can be attached thereto or mounted thereon in any of various ways which will still be characterized by the fact that these removable thrust taking elements are arranged directly at the axis 105 and in a protecting chamber which permits lubrication and prevents the access of foreign material. The devices for attaching, mounting and adjusting the movable closure or cover 15 can be modified and other forms 110 of locks or retaining devices can be substituted for that which I have shown.

What I claim is:

1. In a mechanism for mounting and holding a car axle, having a journal part 115 and a wheel inside of said journal part, the combination of a journal box engaging with the journal part of the axle, a thrust element removably connected to the axle, an oppositely situated second thrust element, 120 said thrust elements being arranged to bear against each other at points which are proximate to the axis of the axle, and a carrier for the second thrust element adapted to hold it stationary axially of the axle 125 and to be moved bodily therewith independently of the box and of the axle.

2. The combination of the wheel, the axle, the box outside of the wheel, the thrust element carried by the axle at its axis, the 130

cover part of the box bodily movable from an open position to a closed position, the lock for automatically engaging with and holding the said cover part in either of said 5 positions, and a second thrust element carried by said cover part and normally situated at the axis of the axle.

3. The combination of the axle, the track wheel, the journal box provided with means 10 for preventing relative longitudinal movement of the axle and having a cover or closure part sliding vertically in planes outside of the end of the axle from a closed position to an open position, and a lock in vertical planes between said closure part and the wheel and adapted to automatically engage with and hold the closure in either of 15 said positions.

4. The combination of the car frame, the journal box, an axle having its end journaled in the box, a wheel on the axle inside of the box, a vertically slideable closure for the box permanently attached thereto and adapted, while so attached, to be moved to an open position to permit access to the 25 axle journal and to the interior of the box, and a spring-pressed latch mounted on the underside of said box and automatically engaging said closure to lock it in either its open position or its closed position. 30

In testimony whereof, I affix my signature, in presence of two witnesses.

NILS D. LEVIN.
